FIG. 1 is a perspective top front right side view of a device with a housing and a base for measuring running speed, running distance and step frequency showing my new design;

FIG. 2 is a perspective view bottom front left side view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right side view thereof;

FIG. 9 is a perspective top front left side view thereof; and,

FIG. 10 is a perspective bottom front right side view thereof.
